UNITED STATES PATENT OFFICE.

REGINALD F. HALLIWELL, OF RUGBY, ENGLAND, ASSIGNOR TO GENERAL ELECTRIC COMPANY, A CORPORATION OF NEW YORK.

ELASTIC-FLUID ENGINE.

1,269,535

Specification of Letters Patent. Patented June 11, 1918.

Application filed February 15, 1917. Serial No. 148,858.

To all whom it may concern:

Be it known that I, REGINALD F. HALLIWELL, a subject of the King of Great Britain, residing at Rugby, Warwickshire, England, have invented certain new and useful Improvements in Elastic-Fluid Engines, of which the following is a specification.

The present invention relates to elastic-fluid engines of the low pressure or mixed pressure type, such as are particularly intended to be fed with elastic fluid from an accumulator, which accumulator may be connected to receive elastic fluid from one or more high pressure engines.

15 The object of my invention is to provide an improved valve mechanism for controlling the flow of elastic fluid from the accumulator to the elastic-fluid engine, which valve mechanism will function as a combined emergency, shut-off, controlling, and low pressure stop valve.

For a consideration of what I believe to be novel and my invention, attention is directed to the accompanying specification 25 and the claims appended thereto.

In the accompanying drawing, Figure 1 is a diagrammatic view showing my improved valve mechanism applied to an elastic-fluid turbine; Fig. 2 is a vertical sectional view through the valve mechanism of Fig. 1, and Fig. 3 is a view similar to Fig. 2 of a modification. In Figs. 2 and 3 the valve operating mechanism of the turbine is shown as turned through an angle of 90° from what it is in Fig. 1 in order to better illustrate the structure.

Referring to the drawing, 5 indicates generally an engine adapted to be driven in whole or in part by low pressure elastic fluid. In the present instance a mixed pressure elastic-fluid turbine is shown having a valve chest 6 to which high pressure elastic fluid may be admitted by the pipe 7. In the valve chest is a suitable valve mechanism, a portion of which is housed by the casing 8. This valve mechanism may be of any suitable type adapted to be operated by the rotation of a shaft 9 to admit elastic fluid from the chest to the turbine. 10 indicates a fluid-actuated motor, to the piston of which is connected a rod 10^a having a rack 10^b at its upper end. The rack 10^b meshes with a suitable gear segment (not shown) on shaft 9 through which the shaft 65 is turned. 11 indicates a speed governor

which is connected to the pilot valve of the motor 10 by governor lever 11^a and rod 11^b. This is a usual and well known arrangement of governor, fluid-actuated motor, and valve gear.

Referring now particularly to Fig. 2 wherein my improved valve mechanism for controlling the flow of low pressure elastic fluid to the engine is shown, 13 indicates an ordinary equilibrium valve receiving elastic fluid from a suitable accumulator 14, or other source, through a conduit 15, and allowing it to pass to the turbine through conduit 16. The spindle 17 of this valve is provided with a cross-head 18 to which a rocking lever 19 is pivotally connected. The lever 19 is provided with a movable fulcrum at each end, the fulcrum 20 on the left-hand end being mounted on a screwed rod 21 which can be rotated by means of a hand wheel 22 to raise or lower the fulcrum so that the valve may be utilized as a manually operated stop valve. The screwed rod 21 is journaled in a sliding abutment 23 which is acted upon by a spring 24 tending to force it downward. In the present instance the rod 21 has a head 21^a which engages the upper surface of abutment 23. The abutment 23 is engaged and held against action of the spring 24 by means of a trigger 25 which engages a notch in the abutment 23. Connected with the trigger is a lever 26 by which it may be moved. This lever may be operated manually or otherwise, as found desirable. When the lever 26 is operated, the trigger 25 is moved out of the notch in abutment 23 and the spring 24 forces the screw rod 21 downward and with it the fulcrum 18, thereby causing the valve 13 to close. In this case the valve acts as an emergency valve.

The other fulcrum 27 of lever 19 is connected to a stem 28 carried by piston 29 working in a cylinder 30. The cylinder 30 below the piston 29 is in communication through an aperture 31 with the steam pressure at the steam inlet 15. The upper side of the piston 29 is in communication with the atmosphere and subjected to atmospheric pressure. 31^a is a weight which may be adjusted to regulate the pressure at which the piston 29 operates. When the effective pressure on the upper side of the piston exceeds that on the under side the fulcrum 18 will be forced downward, thus causing the valve 110

to close. This forms a well known type of pressure regulated automatic shut-off valve. Mounted in alignment with the valve spindle 17 is a cylinder 32 provided with a piston 33 having a stem 34 projecting through its lower end adapted, when the piston 33 is forced downward, to engage the upper side of the cross-head 18. The movement of the piston 33 is controlled by means 10 of a pilot valve 35 which controls the admission of motive fluid to the cylinder 32 in a well known manner. The pilot valve 35 has its stem 36 connected at an intermediate point to a floating lever 37. One end of lever 37 is connected to the upper end of the stem 34 of piston 33, while the other end is connected by means of a link 38 to one arm of a bell crank lever 39. The other arm of the bell crank lever 39 carries a roller 40 en- 20 gaging a cam 41 mounted on the cam shaft 9 which, as already stated, operates the high pressure valve mechanism of the turbine. When the turbine is in operation, the pressure of the elastic fluid on the under side of piston 29 tends to open and hold open the valve 13. The amount which the valve can open, however, is limited by the stem 34 which is positioned by the piston 33, which in turn is controlled by the cam 41 on shaft 25 9. When there is an ample supply of low pressure elastic fluid so that its pressure is kept up, then the upper side of cross-head 18 will be against the stem 34. This in substance places the valve 13 directly under the 30 control of the speed governor 11. Assume, for example, that the turbine is operating entirely on low pressure elastic fluid entering through valve 13: then shaft 9 will be in such a position that the high pressure 35 valve mechanism is closed. The valve 13 may occupy some intermediate position with the upper face of cross-head 18 forced against the stem 34 by the pressure of the low pressure elastic fluid acting on piston 29. If now the turbine should speed up, then the 40 governor 11 will actuate the fluid motor 10 causing it to turn the shaft 9 in an anti-clockwise direction, Fig. 2. This turns the cam 41, thus shifting the position of the bell 45 crank lever 39, causing it to raise the pilot valve 35 to admit actuating fluid above the piston 33. The piston 33 is thus forced downward closing off more or less the valve 13 so as to admit less elastic fluid to the 50 turbine to bring the speed back to normal. On the other hand, should the speed decrease, then the same action takes place, except in the opposite direction, the stem 34 moving upward so as to permit the pressure 55 under piston 29 to open farther valve 13, thus admitting more elastic fluid to the turbine to take care of the increased load. In fact, the valve 13 will follow the movements of the stem 34. Should the load on the tur- 60 bine continue to increase, eventually the 65

valve 13 will be wide open. By this time the active portion of cam 41 has passed from under roller 40. Further turning of the shaft 9 due to increase in the load does not affect low pressure valve 13 further but acts 70 to operate the high pressure valve mechanism in chest 6 to admit high pressure elastic fluid to supplement the low pressure supply, the arrangement being such that the high pressure valve mechanism is opened 75 after the low pressure valve mechanism is fully opened. In case of a diminution in the load, the high pressure valve mechanism is closed prior to the closing of the low pressure valve mechanism. It will thus be seen 80 that the arrangement described functions to always operate the turbine as far as possible on low pressure elastic fluid, which is the most desirable arrangement.

In utilizing an accumulator or a pipe line 85 for supplying elastic fluid to a turbine or other engine, it is desirable to always maintain the pressure in the accumulator or pipe line above atmospheric. One reason for this is to prevent air from leaking into the accumulator or pipe line from which it may find its way to the condenser, thus impairing the vacuum. My low pressure valve mechanism takes care of this, for when the pressure of the low pressure elastic fluid falls below the 90 desired value, then the piston 29 will be forced downward by atmospheric pressure closing off to a greater or less extent the valve 13. At such a time the cross-head 18 and stem 34 separate, and, as will be clear, 95 the speed governor 11 will automatically operate the high pressure valve mechanism to admit high pressure elastic fluid to take care of the load. Should the supply of low pressure elastic fluid fail altogether, then, of course, the valve 13 automatically closes due 100 to the air pressure on piston 29.

Ordinarily the fulcrum 20 of lever 19 is stationary. By turning hand wheel 22 valve 13 can be opened or closed manually and 110 fulcrum 20 can be adjusted to any desired intermediate position. The valve 13 may be quickly and automatically closed by the operation of lever 26 to move the trigger 25 and release abutment 23. This permits the 115 spring 24 to quickly close the valve 13. As is obvious, the lever 26 may be moved manually or by any suitable automatic arrangement.

It will thus be seen that the single valve 13 120 is regulated to perform all the functions necessary and desirable for regulating the flow of low pressure elastic fluid to the turbine.

Referring now to the modification shown 125 in Fig. 3, the piston spindle 34 of piston 33, instead of being arranged in alignment with the valve cross-head 18, is connected at 45 with one end of the lever 19, and the atmospheric cylinder 30 has its piston stem 28 con- 130

nected to one end of an intermediate lever 46. The other end of lever 46 is connected by a rod 47 to the bell crank lever 39, and at an intermediate point it is connected by a rod 48 to the floating lever 37. The space above the piston 29 is in communication with the elastic fluid pressure at the inlet 15 by means of a pipe 49, the under side of piston 29 being subject to atmospheric pressure. With this arrangement the work of moving the main valve 13 is not performed by the atmospheric cylinder 30 and piston 29 directly, as in Figs. 1 and 2, but through the pilot valve 35 and piston 33. The arrangement of levers and the length of the stroke of piston 29 is such that if the elastic fluid pressure at the inlet is less than the desired pressure, the bell crank lever 39 is unable to move pilot valve 35 sufficiently to open valve 13. When the pressure of the steam inlet is high enough, the piston 29 is forced downward and the main valve 13 can be opened by the fluid-actuated piston 33 if the cam gear 41 is in a position for doing so.

The modification of Fig. 3 involves simply a different arrangement of the elements of Fig. 2, and the operation will be readily apparent from the description already given.

In connection with Fig. 3, it will be noted that when the fulcrum 20 is in its lowest position, the valve 13 is shut and the operating piston 33 is at the top of its stroke. With the fulcrum in this position, therefore, the regulating means cannot open the valve 13. On the other hand, if the fulcrum 20 is in its highest position, then with piston 33 at the top of its stroke, the valve 13 will be wide open and it will only be closed when the piston 33 is at the bottom of its stroke.

In other words, it requires a complete movement of the piston 33 from the bottom of its stroke to the top of its stroke to fully open valve 13. Variations in the position of the fulcrum 20 between these two extremes will produce variations in the action of the regulating means on the valve, the position of the fulcrum determining the amount which the valve can open. For example, with the fulcrum about midway between the two extremes, as shown in Fig. 3, it will be seen that the valve 13 is closed when piston 33 is in about the middle position. With this adjustment of the fulcrum 20 the valve 13 can accordingly be opened only half way.

It will thus be seen that the action of the regulating means on the valve 13 depends on the position to which fulcrum 20 is adjusted. This is likewise true of the arrangement shown in Fig. 2, as is obvious, since it requires a full movement of piston 29 from its lowermost to its uppermost position in order to fully open the valve 13. In Fig. 2 the parts are shown in about middle position the same as in Fig. 3.

In accordance with the provisions of the

patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. The combination with an engine adapted to be operated by low pressure elastic fluid, of a valve mechanism for controlling the flow of such elastic fluid, and regulating means for the valve mechanism comprising means responsive to the speed of the engine, and means responsive to the pressure of the low pressure elastic fluid, and a manually operable device for moving the valve mechanism independently of said regulating means, whereby the effective action of the regulating means on the valve mechanism may be varied.

2. The combination with an engine adapted to be operated by low pressure elastic fluid, of a valve mechanism for controlling the flow of such elastic fluid, and regulating means for the valve mechanism comprising means responsive to the speed of the engine, and means responsive to the pressure of the low pressure elastic fluid, a manually operable device for moving the valve mechanism independently of said regulating means, whereby the effective action of the regulating means on the valve mechanism may be varied, an abutment connected to the valve mechanism, means acting on the abutment tending to move it in a direction to close the valve mechanism, a trigger for holding the abutment, and means for releasing the trigger.

3. The combination with an engine adapted to be operated by low pressure elastic fluid, of a valve mechanism for controlling the flow of such elastic fluid, and regulating means for the valve mechanism comprising a lever connected therewith, means responsive to the load on the engine, and means responsive to the pressure of the elastic fluid for raising and lowering the lever, an adjustable fulcrum for the lever, and manually operated mechanism for varying the position of the fulcrum to regulate the valve mechanism.

4. The combination with an engine adapted to be operated by low pressure elastic fluid, of a valve mechanism for controlling the flow of such elastic fluid, and regulating means for the valve mechanism comprising a lever connected thereto, a normally fixed fulcrum for the lever, means responsive to the load on the engine and means responsive to the pressure of the elastic fluid for raising and lowering the lever, means for moving the lever on its fulcrum, manually op-

- 4
- erated means for adjusting the normally fixed fulcrum, and means for releasing the fulcrum to permit the valve mechanism to quickly close.
5. In combination, an elastic-fluid engine having a valve mechanism for admitting low pressure elastic fluid thereto, and a valve mechanism for admitting high pressure elastic fluid to supplement the low pressure supply, means responsive to the load on the engine for regulating said valve mechanisms, means for regulating the low pressure valve mechanism in accordance with the pressure of the low pressure elastic fluid, manually operable means for positioning the low pressure valve mechanism, said means being operable to adjust the valve mechanism independently of both the load responsive regulating means and the pressure responsive regulating means, and means adapted to be released to permit the low pressure valve mechanism to quickly close independently of the other regulating means.
- 25 6. In combination, an elastic-fluid engine, an accumulator for supplying low pressure elastic fluid thereto, a valve mechanism for admitting high pressure elastic fluid to the engine, a valve mechanism for controlling the flow of low pressure elastic fluid from the accumulator to the engine, means responsive to the load on the engine for successively operating said valve mechanisms,
- 10 said means including a floating lever connected between its ends to the low pressure valve mechanism, an adjustable fulcrum for one end of said lever, and a movable abutment responsive to the pressure of the low pressure elastic fluid operatively connected to the other end of said lever.
- 15 7. In combination, an elastic-fluid engine, an accumulator for supplying low pressure elastic fluid thereto, a valve mechanism for admitting high pressure elastic fluid to the engine, a valve mechanism for controlling the flow of low pressure elastic fluid from the accumulator to the engine, means responsive to the load on the engine for successively operating said valve mechanisms, said means including a floating lever connected between its ends to the low pressure valve mechanism, an adjustable fulcrum for one end of said lever, a movable abutment responsive to the pressure of the low pressure elastic fluid operatively connected to the other end of said lever, and releasable means for supporting the adjustable fulcrum.
- 20 In witness whereof, I have hereunto set my hand this thirteenth day of January, 1917.
